UNITED STATES PATENT OFFICE.

HARRIET G. ARMSTRONG, OF CHICAGO, ILLINOIS.

IMPLEMENT FOR MAKING RUGS.

1,323,733.

Specification of Letters Patent.

Patented Dec. 2, 1919.

Application filed December 13, 1918. Serial No. 266,541.

To all whom it may concern:

Be it known that I, HARRIET G. ARMSTRONG, a citizen of the United States, residing at Chicago, in the county of Cook and State of Illinois, have invented certain new and useful Improvements in Implements for Making Rugs, of which the following is a specification.

This invention relates to means for making so-called rag rugs, carpets or the like wherein the weft strands are composed of tightly rolled, twisted, folded or otherwise compressed strips of cloth, the weft strands being bound together by warp threads united therewith either in the usual manner of weaving, or by interlocked stitching, or otherwise; and the principal object of the invention is to produce a simple, easily manipulated and inexpensive hand tool or implement by the use of which the domestic manufacture of such articles can be facilitated and expedited.

My invention, its manner of use, and the advantages for home manufacture of rag rugs, carpets and the like articles inherent therein will all be readily understood by those skilled in the art from the following detailed description, taken in connection with the accompanying drawing, wherein—

Figure 1 is a perspective elevation, broken out between its ends, of a device illustrating one practical embodiment of my invention;

Fig. 2 is a cross section of the same on an enlarged scale, looking toward the front end of Fig. 1;

Fig. 3 is a side elevation, broken out between its ends, of a slightly different embodiment of the same inventive principle; and

Fig. 4 is an enlarged cross section of Fig. 3.

Referring first to Figs. 1 and 2, 5 designates as an entirety a hollow cylinder or mandrel constituting the body on or around which the weft strands are laid during the building up of the rug. This mandrel is formed with a longitudinal under-cut kerf or groove 6, disposed parallel with the axis of the mandrel in which are slidably mounted a series of hooks for holding the weft strands in parallel relation to each other during the formation of the rug. Each of these hooks may be bent to form from a single length of wire and possess substantially the shape illustrated clearly in Fig. 2. More specifically, each of these hooks comprises a head portion 7 lying within and

loosely fitting the under-cut portion of the groove or channel 6, a narrow shank or neck portion 8 lying within the narrow portion of the groove, and a pair of oppositely facing hook-ends 9 that project above the surface of the mandrel.

On one end of the mandrel there is formed an annular flange or bead 10 that constitutes a stop or guard for the first weft strand of the rug, to prevent the latter from slipping off that end of the mandrel as the building up of the rug proceeds.

In the use of the device, one end of the weft strand is first impaled on one prong 70 of the end hook, as shown at 11 in Fig. 1. The strand is then carried around the mandrel against the bead 10 and is then looped over the opposite prong of the same hook, as shown at 12 in Fig. 1, thereby forming the first strand of the rug. The strand is then passed again around the mandrel in the opposite direction closely adjacent to the first strand, after which it is looped over the opposite prong of the second hook, as shown at 13 in Fig. 1. The two strands are then united by warp threads passed therearound by means of an ordinary hand sewing needle or any other suitable hand implement, and suitably interlocked so as to both bind the weft in snugly coiled or folded condition and bond the strands tightly together. This done, the weft strand is again carried around the mandrel and looped over the opposite prong of the second hook, and the third strand is then similarly united to the second. These operations are repeated until the mandrel is completely covered, or until a rug of the desired length has been made. The rug, with the hooks 95 is then slid lengthwise off the other or remote end of the mandrel (Fig. 1), and the hooks are removed by hand, the rug being then completed.

The form of the invention illustrated in Figs. 3 and 4 embodies the same structural principle. In this case, instead of mounting the hooks slidably in a groove or channel of the mandrel, I employ simple S-hooks 14, the eyes of which are slidably mounted on a rod 15 that is in turn removably mounted 100 in a pair of apertured lugs 16 secured to the ends of the mandrel 5'. The pin is held in place by a pivoted spring guard or keeper 17 engaging the end thereof in the manner clearly shown in Fig. 3.

The method of forming the rug on this device is identical with that already de-

scribed in connection with Figs. 1 and 2. When the rug is completed, the keeper 17 is swung to one side, the pin 15 is withdrawn, and the two sides of the rug, with the hooks therein, fall apart, thus freeing the rug from the mandrel, and the hooks are then removed by hand and again strung on the pin 15 in readiness for further service in the making of another rug.

10 It is believed that the structure, manner of manipulation, and advantages particularly for home use of the simple device herein disclosed for making rag rugs and carpets and like articles will readily be understood and appreciated by those skilled in the art of textile manufactures and particularly rug making, without further detailed description. It is believed that the principle of employing a cylinder or mandrel and a series of hooks extending lengthwise of the surface thereof on which the successive weft strands are built up by laying them side on the surface of the mandrel with the folded or looped ends engaged and held by the hooks is broadly new, and it is manifest that numerous structural variations of the forms of the invention shown and disclosed may be made without involving any departure from the principle of the invention or sacrificing any of the advantages thereof. Hence, I reserve all such variations and modifications as fairly fall within the substance and purview of the appended claims.

I claim:

1. An implement for making rugs, comprising, in combination, a mandrel, a series of hooks, and means for supporting said hooks in a line lengthwise of said mandrel. 35

2. An implement for making rugs, comprising, in combination, a mandrel, a series 40 of hooks, and hook supporting and guiding means disposed lengthwise of said mandrel on which said hooks are slidably mounted.

3. An implement for making rugs, comprising, in combination, a mandrel having 45 a stop bead or flange at one end, a series of hooks, and means for slidably supporting said hooks lengthwise of the surface of said mandrel.

4. An implement for making rugs, comprising, in combination, a mandrel having a stop bead or flange at one end, a series of hooks, and means for slidably and removably supporting said hooks in a line disposed 50 lengthwise of the surface of said mandrel. 55

5. An implement for making rugs, comprising, in combination, a mandrel having a stop bead or flange at one end, a series of hooks each disposed transverse to the axis of said mandrel, and guiding and supporting 60 means for said hooks extending lengthwise of the surface of said mandrel and on which said hooks are slidably and removably mounted.

HARRIET G. ARMSTRONG.
